PAPER TOWEL HOLDER

Clifford F. Carroll, Box 76,
Cave Creek, Ariz. 85331

Filed June 6, 1972, Ser. No. 260,348

Term of patent 14 years

Int. Cl. D6—99

U.S. Cl. D52—2 C

FIG. 1 is a perspective view taken from the front and left end of a paper towel holder showing my new design; FIG. 2 is a perspective view taken from the rear and right end thereof; and

FIG. 3 is a fragmentary elevational view thereof, with a portion shown in section for convenience of illustration.

I claim:

The ornamental design for a paper towel holder, as shown.
